(57) **CLAIM**

The ornamental design for a “transition edge for a modular floor tile system,” as shown and described.

DESCRIPTION

FIG. 1 is a perspective view from upper left rear of a “transition edge for a modular floor tile system” according to the present invention;

FIG. 2 is a perspective view from the upper left front thereof;

FIG. 3 is a top plan view thereof;

FIG. 4 is a front elevation view thereof;

FIG. 5 is a bottom plan view thereof;

FIG. 6 is a left end elevation view thereof; and,

FIG. 7 is a right end elevation view thereof.

The broken line showing of environment is included for the purpose of illustrating only and forms no part of the claimed design.

Primary Examiner — Jeffrey D Asch

Attention is directed to the decision of *Snap Lock Industries, Inc v. Connor Sport Court International*, U.S. District Court-Utah (Central) Docket No. 2:10cv294 relating to
this patent. This reexamination may not have resolved all
questions raised by this decision. See 37 CFR 1.552(c) for
ex parte reexamination and 37 CFR 1.906(c) for *inter
partes* reexamination.
